UNITED STATES PATENT OFFICE

133,049

DESIGN FOR A FOLDING STOVE

Bestor Robinson, United States Army,
Oakland, Calif.

Application May 29, 1942, Serial No. 107,048

Term of patent 3½ years

To all whom it may concern:

Be it known that I, Bestor Robinson, United States Army, a citizen of the United States, residing at Oakland, California, have invented a new, original, and ornamental Design for a Folding Stove, of which the following is a specification, reference being had to the accompanying drawing, forming part thereof.

Fig. 1 is a perspective view of a folding stove, showing my new design, and

Fig. 2 is a plan view thereof.

I claim:

The ornamental design for a folding stove, as shown.

BESTOR ROBINSON.
